UNITED STATES PATENT OFFICE

MICHAEL J. KWARTZ, OF DETROIT, MICHIGAN

FOUNTAIN PEN

Application filed July 14, 1930. Serial No. 467,807.

This invention relates to fountain pens and more particularly to a novel form of writing point or nib provided with a rotatable writing element held therein in suitable manner.

Among the objects of the invention is a nib or writing point which permits the use of the pen on any kind of writing surface without scratching or hanging in the fibers thereof.

Other objects will readily occur to those skilled in the art upon reference to the following description and the accompanying drawing in which.

15 Fig. 1 is a side elevation of a portion of the nib.

Fig. 2 is a section on line 2—2 of Fig. 2 and

Fig. 3 is an end view thereof.

20 As indicated in the drawing, the pen may comprise a suitable conventional barrel having held in one end thereof, a tapering point portion over which may fit a suitable cap.

The point portion will be tapered a rather fine dimension and will be provided with an axial duct 13 for leading ink from the barrel 10 to the nib end or writing portion. At its smaller end the point will be provided with a cup like depression 14 in which is mounted the ball-shaped writing element 15. This writing element will be composed of two hemi-spherical sections 15a and 15b mounted upon a suitable spindle 16 extending laterally thru the edges of the cup. As these hemi-spherical portions will preferably be made separately, mounting them upon the spindle will provide a capillary space 17 between them which space will cause flow of ink from the cup above the ball to the lower surface thereof. It is preferred also to cut away the portion of the cup edge as indicated at 18 in order to permit tilting the pen during writing.

The operation of the device will seem to be obvious from the foregoing description and need not be described except to say that the rolling of the ball over the writing surface precludes scratching.

Now having described the invention and 50 the preferred embodiment therof, it is to be

understood that said invention is to be limited, not to the specific details herein set forth, but only by the scope of the claim which follows:

A fountain pen including a barrel having 55 a nib including a conical element having a duct therethru leading to the apex of the element, a writing element in the said apex and consisting of a pair of hemispherical portions with their flat sides adjacent each other and rotatably mounted upon and retained in said apex by a common axle element, said writing element being in position to receive ink from said duct.

Signed at Detroit, county of Wayne and 65 State of Michigan, this 3rd day of July 1930.

MICHAEL J. KWARTZ.
